Application March 8, 1941, Serial No. 382,367

17 Claims. (Cl. 178—29)

This invention relates to printing telegraph apparatus and more particularly to a telegraph apparatus for producing printed tickets or coupons adaptable to accounting systems.

An object of this invention is to provide a coupon or ticket printer which is mechanically simple, accurate in its operation, and inexpensive to manufacture and maintain.

Another object of this invention is to provide a printing telegraph apparatus of the segmented distributor type in which a single magnet is employed to arrest a continuously rotating type wheel and control the printing operation.

The invention features a ticket printer in which the printing magnet, energized in response to received message signals, arrests a normally rotating type wheel in selected positions and effects printing.

The invention also features a ticket printer including a segmented distributor which is connected by a plurality of conductors to a source of signals, such as a device in which the message signals are stored, and a printing magnet, energized by a signal applied to the distributor, which controls the successive application of signals from the storing device to the distributor.

As a further feature of this invention, there is provided a ticket severing means operated to sever a ticket after the stored signals of a single message have been translated and printed on a ticket.

It has sometimes been the custom in the past when operating a printer having a segmented distributor to employ a plurality of magnets, one for each segment of the distributor, operable when energized by a signal applied to the distributor to arrest a rotating type wheel and initiate the printing cycle. When this plurality of magnets was replaced by a single magnet, it was frequently the custom to employ an escapement mechanism, governed by the single magnet, to rotate the type wheel intermittently and to be held inoperative, arresting the type wheel, under the control of a signal applied to the distributor. The printer which is the subject of the present invention employs a single magnet controlling a constantly rotating type wheel and in this manner avoids the mechanical complexities introduced through the utilization of a plurality of magnets or an escapement device.

The objects of the present invention are accomplished by providing a printer which comprises a segmented distributor, a type wheel constantly rotated through a friction clutch, a printing magnet energized to effect printing when the

distributor brushes contact a conditioned segment of the distributor, and a ticket severing means. The armature of the printing magnet operates to arrest the type wheel and move a print hammer into printing relation with the arrested type wheel. Associated with the printer is a signal storing device and a progress switch connected by a plurality of conductors to the several segments of the distributor. The armature of the printing magnet also operates the progress switch to apply the signals of a complete message stored in the storing device, one by one, to the distributor segments to condition them and effect the printing of a toll ticket selectively. 5 The progress switch is provided with means to energize a magnet in the printer which actuates the severing device, cuts the printed ticket from its web and deposits the ticket in a ticket receptacle. 10 15 20 25 30 35 40 45 50 55

For a more complete understanding of this invention reference may be had to the following detailed description to be interpreted with the accompanying drawings in which:

Fig. 1 is a front elevational view of a printing apparatus embodying the features of this invention;

Fig. 2 is a plan view, partially broken away, of the printing apparatus of Fig. 1;

Fig. 3 is a detail view of the printing magnet armature, index wheel, and spacing mechanism;

Fig. 4 is an elevational view taken on the line 4—4 of Fig. 1 and is partially in section;

Fig. 5 is an elevational view taken on the line 5—5 of Fig. 1; and

Fig. 6 is a diagram of the electrical circuit for the printing and cutting magnet and the control circuit for the progress switch.

This invention finds utility in the field of telephone toll operation wherein for the purposes of determining toll charges it is necessary to have a record for each toll call, which record includes the calling subscriber's number, the called subscriber's number, a time and date indication, and similar information. It has been the practice in the past to employ a manual recordation of the toll information but with the printing telegraph apparatus which is the subject of this invention it is possible to have a toll ticket, that is, a record of the toll information, printed automatically. 45 50 55

One method of producing toll tickets automatically contemplates employing the printing apparatus herein disclosed with a storing mechanism in which signal impulses representing the toll information are stored, and utilizing the apparatus, to transfer the stored signals, one by

one, to the printing mechanism for the purpose of recording the toll information on a ticket, and after the information for one call has been entirely transferred to the printer and printed thereat on a ticket, severing the ticket from the web.

Referring now more particularly to Fig. 1 there is illustrated at 11 a structural member for supporting the printing apparatus. Member 11 is secured by means of bolts 12 to an upright frame structure 13 (Fig. 2) upon which any suitable number of ticket printer supporting frames may be assembled in superposed relation. A constantly operating motor 14 is supported on each member 11 for driving the printing apparatus associated therewith. Secured to motor shaft 16 is a worm 17 engaging a fibre gear 18 which forms the driving portion of a friction clutch. Gear 18 and the friction clutch, as well as the remaining parts of the printing apparatus which rotate, are carried upon a shaft 19 supported by an elongated bearing 21 (Figs. 2 and 5) provided with a flanged portion 22 and secured to member 11 by suitable binding screws 23. The friction clutch supported on rotatable shaft 19 comprises the driving gear member 18, a pair of friction discs 26, and a driven disc 27 which carries a driving pin 28. One of the friction discs 26 is interposed between a flanged collar 29 which is secured to shaft 19 by a set screw, and the other friction disc 26 is interposed between gear 18 and disc 27 disposed on the side of gear 18 opposite to that on which flanged collar 29 is located. A collar 31 is carried by shaft 19 and secured thereto by a set screw. A pin 32 is supported by collar 31 and disposed parallel to shaft 19 and extends into the path of pin 28 secured to disc 27 to be driven thereby when shaft 19 is free to rotate. The coil spring 33 disposed about shaft 19 and located between collar 31 and disc 27 exerts a compressive force against the elements of the friction clutch tending to maintain power transmission from drive gear 18 through the clutch to shaft 19.

Shaft 19 has secured thereto by a set screw a collar 36 of suitable insulating material, and collar 36 carries for rotation therewith an arm 37 of a distributor 38. A set of distributor brushes 39 is carried by arm 37 and one brush of the set contacts a closed conducting ring 41 and the second brush of the set successively engages the segments 42 of the distributor. The conducting ring and segments of the distributor are mounted in an insulated disc 43 which has a central aperture in which collar 36 is free to rotate. A second insulating disc 44 is provided for the distributor and mounted intermediate the insulating disc 43 and the elements of the friction clutch for the purpose of protecting the electrical connections to the conductive elements mounted in disc 43 which connections (not shown) are disposed between the insulating discs 43 and 44. Disc 44 is also provided with a central aperture large enough to freely accommodate the coil spring 33 which surrounds shaft 19. A plurality of supporting rods 46 extend parallel to shaft 19, and each rod 46 is secured at one end to the supporting structure 11 and its opposite end carries the aforescribed insulated discs.

To the front portion of shaft 19, as viewed in Fig. 2, are secured an index wheel 47 and a type wheel 48. The index wheel 47 is provided with as many depressions as there are characters on the type wheel so that by means of a stabber, which will be described hereinafter, which engages a depression of the index wheel 47, the type wheel

may be arrested with any of its characters located in the printing position. The type wheel 48 may be provided with as many characters as desired. In the particular embodiment of the invention under discussion there are 12 characters on the type wheel; namely, the ten numerics, a dash, and an asterisk. With this particular type wheel the printed ticket will comprise groups of numerics indicating the called and calling number, the time, etc., but it is to be understood that a type wheel containing additional characters and including letters may be employed if desired.

The printing magnet 51 is secured to member 11 by a Z-shaped strap 52, and its armature 53 which is of yoke form, is pivotally supported upon a stud 54 (Fig. 1) extending between frame member 11 and the depending portion of strap 52. Extending from that portion of the yoke shaped armature 53 nearest to the structural member 11 is an armature extension 55 which is provided with the following projections: a projection 56 (Figs. 2 and 3) extending through an aperture 57 in frame member 11 which operates a pair of contacts 166 supported on the reverse side of supporting member 11; a projection 58 extending perpendicularly of the armature extension 55 and serving as the print hammer; and a tooth-shaped projection 59 (Fig. 3) extending forwardly of the armature extension which serves as a stabber and is introduced into a depression of the index wheel 47 when magnet 51 is energized to arrest the type wheel in a given position. An adjustable stop abutment 61 is secured to member 11 by shoulder screws 62 which project through slotted apertures in the abutment 61 and serves to limit the counterclockwise rotation of armature 53 when the armature is returned to its normal position upon the de-energization of magnet 51. A similar abutment 63 adjustably secured to member 11 serves to limit the clockwise rotation of armature 53 upon the energization of magnet 51. A restoring spring 64 extending between the armature and a spring anchor pin 65 returns the armature to normal position upon the de-energization of magnet 51.

A roll support 67 rotatably mounted on member 11 carries the supply of web 68 from which printed tickets are to be produced. The web passes from the supply over a guide roll 69 rotatably carried by a pin 71 secured to member 11, thence over a rotatably supported roll 72 to cooperating feed rolls 70, 73 and 74 which cause an intermittent feed of the web along a web guide 75 to the printing point. Guide roll 72 is rotatably supported upon a shaft 76 which is carried in a pivoted frame comprising frame members 77 and 78 (Fig. 2) pivotally supported on pin 71. With the web threaded through the apparatus in the above described path the feed rolls 70, 73, and 74, when arrested, serve to hold the web from movement, and the pivoted frame carrying guide roll 72 tends under its own weight to rotate in a counterclockwise direction and thus tends to exert an unreeeling torque upon the supply of the web to form a tape loop between the supply reel 67 and the feed rolls. This tape loop affords a smoother web feed by removing the inertia of the supply as a load from the feeding rolls. The web guide plate 75 is provided with an aperture 79 (Fig. 1) at the printing point through which the print hammer 58 is projected upon the energization of magnet 51 to present the web to the type wheel.

Feed roll 73 is mounted to rotate upon a shaft 81 when that shaft is rotated by a driving ratchet

82 (Fig. 3) disposed thereon intermediate structural member 11 and feed roll 73 (Fig. 5). Feed ratchet 82 is rotated intermittently by a feed pawl 83 (Fig. 3) pivotally mounted on a lever 80 which, in turn, is pivoted on stud 54. Lever 80 is provided with a slot 85 through which an eccentric 84 carried by armature extension 55 projects. The eccentric enables an adjustment of lever 80 with respect to the armature. A comb 90, extending from the stop element 61 serves to space the armature and feed pawl and to guide their rotative movements.

The slot 85 permits relative movement between the feed pawl 83 and the armature 53 so that when the magnet 51 is energized the only load it must overcome initially is that of the armature 53. This relative movement of the armature with respect to the feed pawl enables the stabber 59 to engage the index wheel 47 and arrest the type wheel 48 before the feed pawl is elevated. The armature raises the feed pawl 83 after it has moved toward the magnet and come within a stronger magnetic field. A spring 86 angularly disposed with respect to feed pawl 83 serves to rotate the pawl toward the feed ratchet 82 when magnet armature 53 has elevated the feed pawl above the ratchet, and spring 86 also supplies a feeding force to the pawl when magnet 51 is de-energized and spring 86 is free to move pawl 83 downwardly on its feeding stroke. A stop 87 secured to member 11 serves to limit the downward movement of feed pawl 83 and the length of its feeding stroke and thereby prevent an over-feed. A spring pressed deterrent 88 pivotally supported on stud 89 holds the feed ratchet when pawl 83 is elevated preparatory to the feeding stroke. Feed roll 73 is provided with a covering of rubber or any other suitable material having a high co-efficient of friction to afford good feeding contact between the feed roll and the web. Rolls 70 and 74 are rotatably supported on individual shafts which are in substantial axial alignment. Each shaft is secured to an arm 91 (only one of which is shown) which is pivotally mounted on a pin 22. Pressure roll 74 is normally held in cooperation with feed roll 73 by a spring 93 distended between anchor pin 65 secured to frame member 11 and a cross pin 96 carried by pivoted arms 91.

A tape-out indicator is provided to cause an indication when the supply of tape is exhausted or reduced to a predetermined amount. The tape-out indicator comprises essentially a follower arm 97 (Fig. 1) adapted to ride upon the periphery of the web supply, and this follower is secured to a rock shaft 98 rotatably supported in member 11 and carrying a lever 99 on the reverse side of member 11. A contact pair 101 has an insulated projection 102 extending within the arcuate path of lever 99 described as rock shaft 98 is rotated. Contact pair 101 is adapted to close any suitable circuit (not shown) to operate a visual or audible signal indicating that the tape has been spent to a predetermined amount. In operation, the follower 97 rides upon the periphery of the web supply and as the web is paid out, diminishing the diameter of the supply gradually, the follower 97 rocks rock shaft 98 in a clockwise direction until lever 99 engaging projection 102 causes the contact pair 101 to be operated and complete the indicating circuit.

A ticket receptacle 103 is carried upon a base plate 104 adapted to be slidably carried by frame member 11 through the agency of supporting studs 105 extending from member 11 through

slotted apertures 106 of base plate 104. The receptacle comprises frame elements 107, and 111, and U-shaped frame elements 108 and 109 (Figs. 1 and 4). Elements 108 and 109 are secured at their web portions to element 107 and at their extremities by strips 114 and 116, defining, through this assemblage, a container. That end of each strip disposed nearest to the printer is deflected outwardly to define a converging entrance to the receptacle, and each strip is provided with a flanged portion 115 extending throughout the length thereof and these flanged portions serve as a guideway to support a web as it is introduced into the receptacle from the printer. Each flange is deflected downwardly at the entrance of the receptacle to assure that a strip being fed into the receptacle will rest upon the guideway. The receptacle is provided with a ticket receiving platform 112 normally retained by a compression spring 113 near the top of the receptacle just beneath the ticket guideway to retain the severed tickets deposited thereon, in a manner to be hereinafter described, in stacked relation by urging them against the under side of the strip guideway. After a sufficient number of tickets has been accumulated in the receptacle 103, frame member 111 which is secured by means of a hinge 117 to the web portion of element 109 may be rotated to provide a suitable opening through which the tickets may be removed. This frame member 111 is normally retained in its vertical position by an L-shaped latch 119 pivoted at 121 to the base of the receptacle 103 and urged into latching position by spring 118 extending from the latch and secured to a spring post carried by the base of the receptacle. When member 111 is rotated out of the path of latch 119 the counterclockwise rotation imparted to the latch by spring 118 is limited by the engagement of the latch arm with frame element 108 (see Fig. 2). Secure to frame member 107 of the receptacle 103 is a knife edge 122 which in cooperation with a pivoted blade 123 comprises the ticket severing means.

The ticket receptacle and severing means are mounted on member 11 and may be adjusted with respect to the printing point to vary the length of the ticket. Member 11 is cut away as indicated at 124 to afford a recess within which a mounting block carrying the receptacle and ticket severing means is adjustably located. The mounting block located within the recess provided in member 11 is indicated by numeral 126 (Fig. 4) and the mounting plate 104 of the receptacle is secured thereto. Mounting block 126 also carries a supporting bracket 127 upon which the severing mechanism is located. The severing mechanism is operated by a cutting magnet 128 carried in bracket 127 and provided with an armature 129 carried by a pivoted frame structure comprising a U-shaped frame member 131. Frame member 131 is pivotally supported upon a shaft 132 mounted in bracket 127, and a spring 133 surrounding shaft 132 urges frame 131 rightwardly within the bracket 127 and on shaft 132, as viewed in Fig. 2, so that the knife edges of the severing device are maintained in a severing relationship with one another. The blade element 123 is provided with a depending projection 134 extending below the upper surface of the knife edge 132 to prevent the blade 123 from overlapping the knife edge. The knife blade 123 is adjustably secured to the U-shaped frame member 131 as indicated in Fig. 5. One arm of the U-shaped frame member 131 carries a pair

of pressure blades 136 and 137 disposed parallel with and intermediate the guide strips 114 and 116, and a limiting blade 138 integral with bracket 127 overlaps at its extremities the arms of U-shaped frame member 131 to limit the clockwise rotation of the frame member about shaft 132 when magnet 128 is de-energized. A bell crank 139 secured to frame member 131 and pivoted about shaft 132 is rotated in a clockwise direction by a spring 141 extending between bracket 127 and the depending arm of the bell crank when the cutting magnet 128 is de-energized to restore the knife blade 123 to its elevated position. The depending arm of the bell crank 139 operates a set of contacts 142 as it rotates about shaft 132. The web after it passes the printing point is guided by web guide 75 into the ticket receptacle upon the guideway 115 formed by the flanges of strips 114 and 116. When the ticket is to be severed and the cutting magnet becomes energized, the frame member 131 is rocked in a counterclockwise direction under the action of the magnet in attracting its armature whereby the blade 123 in cooperation with knife edge 122 severs the printed ticket, and the pressure blades 136 and 137 depress the severed ticket beneath the guideway 115 and onto platform 112 which serves to hold the accumulated tickets when the blade 123 is elevated. In this way the guide 115 is cleared of the severed ticket and there is no obstruction in the path of the web as it is subsequently fed from guide 75 in the preparation of another ticket and, therefore, the web may be fully received on the guideway as the printing cycle proceeds.

Roll 73 of the web feeding device has at one extremity the type band 146 (see Fig. 2) upon which are carried identifying indicia for the particular printer. As the pressure rolls feed the web to the type wheel the type band 146 prints a character on the underside of the web to identify the printer on which any given ticket has been prepared. By mounting pressure rolls 74 and 76 on individual shafts, they may cooperate with feed roll 73 and print band 146, respectively, even though the diameters of the feed roll and the print band are not exactly the same.

There is provided on stud shaft 147 (Fig. 1) carried by member 11 a U-shaped member 148 which carries an inking roller 149 and an applicating roll 150 which applies the ink to the type wheel 48. Frame member 148 has an extension 151 projecting above the periphery of the ink wheel 149 which serves as a guide to prevent the web loop of the printer which may be disposed above the particular printer from coming into contact with the inking roll 149. A similar inking system for type band 146 is indicated at 152.

The control circuit for the printer is shown in Fig. 6 wherein there is indicated at 156 a storing device in which the signals comprising the toll messages to be printed on a toll ticket are stored. Associated with the storing device 156 is a progress or sequence switch 157 which operates to transfer the signals stored within the storing device, one by one, to the printing apparatus. The progress switch 157 comprises a plurality of contact banks and each one of such banks is connected over an individual conductor 158 to each individual segment 42 of the distributor. One bank of contacts is connected by a conductor 159 to the cutting magnet 128 to battery 161 and ground. A ratchet 173 is included in the progress switch which may be advanced by a pawl 171 to

step the switch through its successive contact engaging positions. The printing magnet 51 is connected from grounded battery over a conductor 162 to the solid conducting ring 41 of the distributor. The progress switch is advanced by means of a stepping magnet 163 which is included in a control circuit including ground, contact pair 142 controlled by bell crank lever 139, conductor 164, contact pair 166 controlled by projection 56 on the armature extension 55, conductor 166a, stepping magnet 163, and battery. A second control circuit delays the application of a message signal from the progress switch to the segments of the distributor following an advancement of the progress switch by the stepping magnet and that control circuit includes ground, contact 142, conductor 164, contact pair 166, conductor 166a, conductor 167, slow-to-operate relay 168, and battery. Slow-to-operate relay 168 when it operates applies ground traced to relay 168 to the storing mechanism.

The progress switch and storing device represented schematically in Fig. 6 comprise no part of the present invention and accordingly the details of those elements have not been disclosed. Any suitable storing device and sequence switch may be employed for those elements but it is preferred that the storing device comprise a group of register relays such as those disclosed in copending application filed by J. W. Gooderham, Serial No. 448,782, filed June 27, 1942. The application to Gooderham also discloses a suitable sequence switch which is to be employed with the register relay. A similar group of register relays, usable in combination with a progress switch, is to be found in Patent No. 1,916,761 to Henry et al. and illustrated in Fig. 8 of that patent at 805—808; 815—818, and 825 and 828. Each contact bank of the progress switch contains as many contact positions as characters in the message to be printed upon a ticket and one additional contact employed when the progress switch is to supply an energizing impulse to the cutting magnet. The storage device in its preferred form places battery from the circuit extended through the armature and contact of slow-to-operate relay 168 to one contact in one of the contact banks of the progress switch 157 at a time and the conductor associated with the particular bank in which the conditioned contact is located extends the ground to its associated segment in the distributor to render that segment conditioned so that when the distributor arm 37 in its rotation carries the brush set 39 into contact with the conditioned segment, the circuit to the printing magnet will be completed through the ground extended from the progress switch through the selected segment of the distributor through brush set 39 to the conducting ring 41 and the remainder of the printing magnet circuit.

Operation

In operation, the signals comprising the messages to be printed on toll tickets are stored in the storing device 156 and at the start of the printing of a given ticket the progress switch is in its initial position which places a ground over the above defined circuit to a selected one of the segments of the distributor, and the shaft 19, which is rotating at this time, brings the set of brushes 39 into engagement with the particular conditioned segment completing a circuit to the printing magnet 51 which attracts its armature, inserting stabber 59 into the depression of the index wheel adjacent thereto at the instant the

printing magnet is energized. There are the same number of depressions in the index wheel as segments on the distributor so that by conditioning any given segment any particular character on the type wheel may be brought into the printing position at the time the stabber arrests the rotation of the type wheel. Armature 53 of magnet 51 in addition to arresting the type wheel elevates feed pawl 83 preparatory to its feeding stroke and projects the print hammer 58 through the aperture 79 in guide plate 75 presenting the web to the type wheel for the reception of an impression of the character in the printing position at that particular moment. This movement of armature 53 opens at contact 166 through the projection 56 of the armature the circuit which has extended the ground from the progress switch to the selected distributor segment and thereby de-energizes the printing magnet 51. In addition to interrupting the circuit to printing magnet 51, projection 56 of armature 53 in operating contact 166 also interrupts the circuit to stepping magnet 163 and slow-to-operate magnet 168.

With magnet 51 de-energized, spring 64 is effective to return armature 53 to its normal position retracting stabber 59 from engagement with the index wheel and permitting the type wheel to continue its rotation, and spring 86, in conjunction with spring 64, is effective to move pawl 83 on its feeding stroke to advance the web. With magnet 163 de-energized, its armature 172 is rotated in a clockwise direction by its restoring spring and causes pawl 171 carried on the armature to engage ratchet 173 and advance it, stepping the progress switch 156, one step. The return of armature 53 closes the contact pair 166 and completes the circuit to stepping magnet 163 which attracts its armature. Although the progress switch 157 has been advanced to its next position at this time, the next signal of the toll message has not been applied to the segments of the distributor because the slow-to-operate relay 168, inserts a delay for the purpose of insuring that the armature of printing magnet 51 will be retracted to effect the release of the type wheel and the feeding of the web. Finally, slow-to-operate relay 168 attracts its armature supplying ground therethrough to the progress switch 157 and another selected segment of the distributor to effect the printing of the following character of the toll message.

The repeated operation of the printing apparatus which effects in sequence the arrestment of the type wheel, the printing of the character, the de-energization of the printing magnet, and the restoration which effects the paper feed and the operation of the control circuit continues until the stepping magnet has advanced the progress switch from its initial to its last position by which the entire toll message is printed upon the toll ticket.

After the progress switch has advanced through a complete cycle and caused the printing of a toll ticket, the ticket must be severed from its web. The severing operation may be effected immediately after the last character of the ticket has been printed or at any convenient time subsequent thereto. In the illustrated embodiment of this invention, the ticket receptacle 103 is spaced a distance corresponding to approximately 24 spacing steps from the printing point and accordingly, the twenty-fourth position of the sequence switch is utilized to energize the above-described cutting magnet circuit. Therefore, after a ticket

has been printed and the apparatus is producing another ticket, the twenty-fourth operation of the apparatus will sever the completed ticket and deposit it in the receptacle. Upon the operation of the cutting magnet 128, bell crank 139 operates the contact pair 142 to disable the circuit to the stepping magnet 163, and advance the progress switch to continue the ticket printing cycle.

10 Although a specific embodiment of the invention has been disclosed and described herein, it is to be understood that the invention is capable of many modifications and rearrangements and, accordingly, the invention is not to be limited to the particular disclosure, but only by the scope of the appended claims.

What is claimed is:

1. In a printing telegraph system, a segmented distributor, a set of distributor brushes, a type wheel, a shaft on which said set of brushes and said type wheel are carried, driving means for said shaft, a printing magnet, means to cause printing from said type wheel upon the energization of said printing magnet, a circuit for said printing magnet including said set of brushes and a segment of said distributor, a signal storing means, means to connect the segments of said distributor individually to said storing means, and means for successively transferring stored signals over said connecting means to said distributor to cause the printing of intelligence.

20 2. In a printing telegraph system, a distributor having a plurality of segments, a set of brushes for cooperation with said segments, a type wheel, a shaft for carrying said set of brushes and said type wheel, means for rotating said shaft, a printing magnet, means controlled by said magnet to effect printing, a circuit for said magnet including said set of brushes and a conditioned one of said distributor segments, a signal storing means, and an individual connection for each segment to said storing means to selectively condition the segment of said distributor in accordance with stored signals.

30 3. In a telegraph system, a signal storing device, a printing machine including a segmented distributor, a set of cooperating brushes, a type wheel, a shaft carrying said type wheel and said set of brushes, a printing magnet effective to cause printing from said type wheel, a circuit for said printing magnet including said set of brushes and a conditioned one of said segments, means connecting said storing device to said distributor, and means controlled by said printing magnet to transfer stored signals to said distributor to effect printing in accordance with a stored message.

40 4. In a printing telegraph apparatus, a signal storing device, a printing apparatus including a segmented distributor, a set of distributor brushes, a type wheel, a shaft carrying said type wheel and said set of brushes, a printing magnet, a circuit for said printing magnet including said set of brushes and a conditioned one of said segments, a plurality of conductors connecting the several segments of said distributor individually to said storage device, and means controlled by said printing magnet to transfer stored signals to said distributor to effect printing from said type wheel in accordance with a stored message.

50 5. In combination, a signal storing device, a printing apparatus including a segmented distributor, a set of rotating brushes cooperating therewith, a type wheel, a rotating shaft carrying 60 said set of brushes and said type wheel, a print-

70 75

ing magnet, means operated upon the energization of said printing magnet to arrest said type wheel and effect printing, a plurality of conductors, a progress switch connecting each segment of said distributor over one of said conductors to said storing device for applying a stored signal to said distributor segments to selectively condition said segments, a circuit for said printing magnet completed upon the engagement of said set of brushes with the distributor segment conditioned by the applied signal, and means controlled by said printing magnet to step the progress switch and apply another stored signal to said distributor after the printing operation initiated by the energization of said printing magnet has been completed.

6. In a printing telegraph system, means to store message signals, a printing apparatus including a type wheel carrying type characters, a distributor having as many segments as type characters on said type wheel, a distributor arm, a set of brushes carried by said arm to engage said segment, a rotating shaft on which said type wheel and distributor arm are fixed, a printing magnet, means operated by the energization of said printing magnet to effect printing from said type wheel, a plurality of conductors connecting the several segments of said distributor to said storing means, means under the control of said printing apparatus to successively apply stored signals over said conductors to said distributor to selectively condition one of said segments, and a circuit to said printing magnet completed upon the engagement of said set of brushes with said conditioned segment.

7. In combination, a signal storing mechanism, a printing apparatus including a distributor, a set of brushes cooperating with said distributor, a type wheel, a rotating shaft carrying said set of brushes and said type wheel, a printing magnet, means operated by said printing magnet to effect printing from said type wheel, a progress switch connected to said storing mechanism, a plurality of conductors connecting said distributor to said progress switch over which a stored signal is applied to said distributor, a circuit for said printing magnet completed upon the engagement of said set of brushes with a conditioned segment of said distributor, a stepping magnet to advance said progress switch to apply the stored signals successively to said printing apparatus, and a circuit for said stepping magnet completed upon the operation of said printing magnet.

8. In a ticket printer, a segmented distributor, a set of brushes cooperating therewith, a type wheel, a rotating shaft carrying said set of brushes and said type wheel, a printing magnet, means controlled by said printing magnet to effect printing from said type wheel, a ticket severing means, a source of message signals, a plurality of conductors connecting the segments of said distributor to said source of signals, means to apply signals one at a time over said conductors to condition said segments, a circuit for said printing magnet completed upon the engagement of said set of brushes with a conditioned segment, and means to operate said severing means after the printing of a ticket.

9. In a message ticketer, a signal storing means, a printing apparatus including a distributor, a rotating type wheel, a printing magnet, an armature for said magnet operable to effect printing from said type wheel upon energization upon said magnet, means to energize said magnet in

accordance with a signal applied to said distributor, means connecting said distributor with said storing means, means to apply signals one by one from said storing means to said distributor to effect the printing of a message ticket, a ticket severing means, and means to operate said severing means after a predetermined number of operations of said printing magnet.

10. In a printing telegraph system, a source of signals, a printing apparatus including a distributor having distributed segments, a set of brushes cooperating therewith, a type wheel, a rotating shaft upon which said set of brushes and said type wheel are mounted, a printing magnet, means operated by said magnet to effect printing from said type wheel, a severing device to sever printed tickets, a cutting magnet to operate said severing device, a progress switch connected to said source of signals, a plurality of conductors extending between said progress switch and said distributor segments over which signals are applied to said distributor, a stepping magnet to advance said progress switch to apply signals one by one to said distributor, a circuit for said printing magnet completed when said set of brushes engages a segment conditioned by an applied signal, means controlled by said printing magnet to energize said stepping magnet, and means operable after a predetermined number of advancements of said progress switch to energize said cutting magnet and operate said severing device.

11. In a ticket printing system, a message signal storing device, a printing apparatus comprising a segmented distributor, a set of distributor brushes, a type wheel, a rotating shaft carrying said set of brushes and said type wheel, a printing magnet, means operated by said printing magnet to arrest a type wheel and effect printing, 35 means for severing a printed ticket, a progress switch having a plurality of contact banks, one of said banks being connected to each segment of said distributor and one bank being connected to said severing means, said progress switch being connected to said storing device to apply stored signals to said distributor, a circuit to said printing magnet completed when said set of brushes engages a distributor segment conditioned by a message signal, means controlled by the operation of said printing magnet to advance said progress switch, and a circuit to said severing means from the bank of contacts of said progress switch connected thereto conditioned to operate said severing means after a predetermined number of advancements of said progress switch.

12. In a message ticket printing system, a signal storing means, a printing apparatus including a segmented distributor, a set of distributor brushes, a printing magnet, means controlled by said printing magnet to effect printing, a progress switch connected to said storing means, a conductor connecting each distributor segment to said progress switch and over which a stored signal may be applied to said distributor, a circuit for said printing magnet completed upon the engagement of said brushes with a segment conditioned by an applied signal, a stepping magnet energized by the operation of said printing magnet to advance said progress switch and apply stored signals one by one to said distributor, and means for delaying the application of a stored signal to said distributor after the operation of said stepping magnet.

13. In a message ticket printing system, a signal storing means, a printing apparatus including

a segmented distributor, a set of distributor brushes, a printing magnet, means controlled by said printing magnet to effect printing, a progress switch connected to said storing means, a conductor connecting each distributor segment to said progress switch and over which a stored signal may be applied to said distributor, a circuit for said printing magnet completed upon the engagement of said brushes with a segment conditioned by an applied signal, a stepping magnet energized by the operation of said printing magnet to advance said progress switch and apply the stored signals one by one to said distributor, and a slow-to-operate relay connected in circuit with said storing means and said progress switch to delay the application of a stored signal to said distributor after the operation of said stepping magnet.

14. In a printing telegraph apparatus, a signal storing means, a printing apparatus including a distributor, a printing magnet, means to apply stored signals to said distributor, means to energize said printing magnet in accordance with a signal applied to said distributor, means operated by said magnet to effect printing, a web supply, means to feed said web to the printing position comprising a pair of friction feeding rolls, and a type band carried by one of said rolls to print on said web periodically a numeric identifying said printing apparatus.

15. In a coupon printer, a source of message

signals, a printing apparatus including a distributor having distributed segments, a plurality of conductors connecting the segments of said distributor to said source of signals, means to apply signals from said source over said conductors to said distributor, means to cause printing in accordance with signals applied to said distributor, and means to sever a coupon after a predetermined number of characters has been printed thereon.

16. In a printing telegraph system, a source of telegraph signals, a printing mechanism including a distributor having distributed segments, a continuously rotating type wheel and a single magnet, a plurality of conductors connecting said distributor segments individually to said source of signals, and means to energize said magnet and cause selective printing from said type wheel in accordance with signals applied to said distributor over said conductors.

17. In a printing telegraph system, a telegraph ticket printer, signal responsive means to advance a web through said printer, a guideway into which said web is advanced from said printer, means responsive after a predetermined number of signals have been received to sever said web, a receptacle for receiving the severed portion of said web, and means to displace said severed portion of said web from said guideway into said receptacle.

WALTER J. ZENNER.
